US00D585878S

(12) **United States Design Patent**
Jung

(10) **Patent No.:** **US D585,878 S**
(45) **Date of Patent:** **** Feb. 3, 2009**

(54) **HEADSET**

(75) Inventor: **Hei-Chae Jung**, Gyeonggi-do (KR)

(73) Assignee: **Unneeds Commerce**, Gyeonggi-do (KR)

(**) Term: **14 Years**

(21) Appl. No.: **29/290,846**

(22) Filed: **Jan. 22, 2008**

(30) **Foreign Application Priority Data**

Jul. 23, 2007 (KR) 30-2007-0031640

(51) **LOC (9) Cl.** **14-01**

(52) **U.S. Cl.** **D14/223**

(58) **Field of Classification Search** D14/205, D14/206, 223; 181/129, 130; 379/430, 446, 379/374, 376, 377, 378, 380, 381; 381/375, 381/385; D24/174

See application file for complete search history.
